PUMP

Edwin E. Tim and Mathias H. Baudendistel, Jr.,
St. Louis, Mo.

Application June 30, 1939, Serial No. 282,182

2 Claims. (CL 36—45)

This invention relates to shoes or pumps.

An object of the invention is to provide a pump which has a throat comfortable to the wearer and yet one which can be produced economically by steps departing as little as possible from conventional methods.

A further object of the invention is to provide means for insuring comfort at the throat of a pump which will accommodate themselves to different commercial methods and materials.

A large number of different expedients have been proposed and employed to give a finish to the throat of a pump which finish will be easier on the foot than the usual exposed seam about the opening of the upper. But these expedients have been expensive, have required a departure from the best and most economical manufacturing methods, and have not been satisfactory in service. The present invention provides comfort and durability while retaining the advantages of the most efficient manufacturing methods.

Other and specific objects will be apparent from the following detail description taken in connection with the accompanying drawings.

Fig. 1 is a perspective view of a shoe embodying this invention;

Fig. 2 is a plan view of a shoe upper in process of preparation and showing an initial step of this invention;

Fig. 3 is a view similar to Fig. 2, showing a side opposite to that of Fig. 2;

Fig. 4 is a view of a closed shoe upper showing a subsequent stage in the preparation of the upper;

Fig. 5 is a detail partly in section of a completed shoe; and

Fig. 6 is a section on line 6—6, Fig. 5; and

Fig. 7 is a view showing details at and adjacent the throat of the completed shoe.

As specifically illustrated the upper includes a vamp 1, a vamp lining 2, a quarter lining 3 and a doubler 4. It will be understood, of course, that the invention is not restricted to the use of any particular materials, and the statements here as to materials are for the purpose of better explaining the invention, and for that reason alone there is given specifically a list of materials which are commonly used. The vamp 1 is usually of leather and commonly of patent leather; the vamp lining 2 is of fabric; the quarter lining 3 is commonly of kid; and the doubler 4 is usually of fabric.

As shown in Figs. 2 and 3 the several enumerated parts of the upper have been cut to pattern.

The vamp lining 2 and the quarter lining 3 have been united by seams 5 to produce a complete lining. The parts have been placed in juxtaposition but both wrong side out for the reasons to be explained later.

The doubler 4 is attached to the flesh side of the leather by adhesive throughout its extent and edges 6 on the vamp are skived, turned over and cemented down on the doubler. A binding strip or tape is often used to finish the edge of the vamp in place of the turned edge portion 6 as specifically illustrated.

The grain or finish side of the vamp and the grain or finish side of the lining are placed face to face, reverse from that in which they will be in the finished shoe. While the parts are in this order and position and as shown in Figs. 2 and 3 a line of stitching 7 is placed around the throat uniting the upper 1 and the quarter lining 3.

After the seam 7 has been stitched the upper is turned, reversing the relationship of the vamp having the doubler 4 secured to it as one part and the linings 2 and 3 as another part. The upper may then be closed at the heel, although this operation may be done before the stitching 7 is run. After the upper has been turned a line of stitches 8 is made entirely around the opening of the shoe except that portion which has already been secured by the line of stitches 7, the stitches 7 and 8 being complementary and together uniting the vamp and lining about the edge of the shoe opening.

As shown in Figs. 2, 3 and 4 the lining is cut so as to leave marginal portions 9, these portions being used for the attachment of a strap or saddle 10 to engage a last and to assist in properly lasting the shoe. After the shoe is removed from the last it is finished by trimming the lining 3 around the edge of the opening to trim away the extended portion 9.

The seam 7 runs along attaching tabs or strips 11 and 12 integral respectively with the vamp 1 and the lining 3 at their throats, each tab being defined by slits at the ends thereof extending inwardly from the marginal edges. That is, in the vamp 1 slits 8a separate the attaching tab 11 from the side edge portions 6 described above, and in the lining, side marginal portions 9 are separated from the attaching tab 12 by slits 9a. Then when the vamp and lining are turned, these attaching tabs 11 and 12 fold inwardly and are covered by the vamp and lining. Rearwardly of the tabs the outer material or vamp has a smooth edge due to the infolding of strip 6, while the

edge of the lining after trimming is raw, as seen in Fig. 6.

It may now be understood that the novel method of seaming the throat and turning the upper produces a smooth portion at the throat of a pump which will be easy on the foot by eliminating the usually open hard seam at this point where considerable pressure is present when the shoe is worn. At the same time, aside from the novel steps of forming and seaming the throat and then turning the upper, conventional methods of manufacture are retained, providing economy and efficiency in the manufacture, with the usual seam around the major portion of the shoe opening to give the usual finish.

It will be understood that since several conventional steps in shoe manufacturing are described as such, various changes may be made in them in combination with the novel features disclosed, within the scope of the appended claims, without departing from the spirit of this invention.

We claim:

1. In a pump, an upper including a vamp and

5 a lining, attaching tabs integral respectively with the vamp and lining and inturned adjacent each other between the vamp and lining, a seam uniting said tabs and covered by the vamp and lining, and an exposed seam through the vamp and lining about the opening of the upper rearwardly of the tabs completing the attachment of the vamp and lining about the opening.

10 2. In a pump, an upper including a vamp and a lining, attaching tabs integral respectively with the vamp and lining and inturned adjacent each other between the vamp and lining, a seam uniting said tabs and covered by the vamp and lining, a strip integral with the vamp along the 15 opening of the upper rearwardly of the tabs inturned between the vamp and lining, and an exposed seam through the vamp, said strip and lining rearwardly of the tabs completing the attachment of the vamp and lining about the opening, the edge of the lining adjacent the last mentioned seam being raw.
